UNITED STATES PATENT OFFICE.

GEORGE D. WILSON, OF BERKELEY, CALIFORNIA, ASSIGNOR TO AMERICAN METER COMPANY, INC., OF NEW YORK, N. Y., A CORPORATION OF DELAWARE.

WRIST-PIN ASSEMBLY FOR METER VALVES.

Application filed February 19, 1927. Serial No. 169,661.

The present invention relates to an improvement in valve cover and valve wrist pin assembly for meters generally and more particularly designed for gas meters as at 5 present universally used.

Heretofore the valve cover and valve wrist pin have been united by solder. This construction while satisfactory at first, becomes, through constant usage, loosened 10 allowing the wrist pin to drop away from the valve cover, thus interrupting the functioning of the valve. To overcome this structural weakness, the uniting of the pin with the valve cover is the principal object 15 of the present invention.

With the above mentioned and other objects in view, the invention consists in the novel construction and combination of parts hereinafter described, illustrated in the accompanying drawings and set forth in the claim hereto appended, it being understood 20 that various changes in the form, proportion, size and minor details of construction may be resorted to without departing from the spirit or sacrificing any of the advantages 25 of the invention.

To comprehend the invention, reference is directed to the accompanying drawings, wherein:—

30 Figure 1 is a perspective view of the valves of a meter and their operating mechanism.

Figure 2 is a plan view of one of the valves with the valve cover arm connected 35 with the valve wrist pin.

Figure 3 is a sectional view taken on line 3—3 of Figure 2.

Figure 4 is a sectional view illustrating 40 the wrist pin mounting shank embedded in the valve cover.

Figure 5 is a sectional view on line 5—5 of Figure 2 illustrating the preferred mounting of the wrist pin within the eye of the shank.

45 Figure 6 is a perspective view of the valve wrist pin illustrating the reduced lower end.

Figure 7 is a perspective view of the shank.

50 Figure 8 is a perspective view of a portion of the valve arm cover which connects with the valve pin when in assembled relation.

In the drawings wherein like characters 55 of reference designate corresponding parts

the numeral 1 indicates the upper compartment of a conventional type meter box. The numerals 2 represent valve seats upon each of which is mounted for horizontal movement a valve seat cover 3, each cover being 60 provided with the conventional valve cover guide wires 4 passing through and reciprocating in wire guides 5, the wires 4 and the guides 5 holding the valve cover in position to reciprocate upon the valve seat. Ex- 65 tending from each valve cover is a shank 6 wedge shaped in plan, the base of said shank being embedded in its associated cover by being cast therein. The shanks so mounted become an integral part with 70 their associated covers as shown in Figure 4 of the drawings and are thus prevented from becoming loosened due to the constant use of the valve. The free end of each shank 6 is provided with an aperture or 75 eye 7. 9 is a cylindrical valve wrist pin having a reduced lower end portion 10 cored as at 10' and one is adapted for insertion within each eye 7 so that the edge of said cored portion may be swaged over the 80 peripheral edge of the eye 7, thus retaining the valve wrist pin within said eye with the shoulder 8 resting on the upper surface of the shank 6 surrounding the eye. The casting of the respective shanks 6 in their 85 associated valve covers insures a rigid and permanent attachment which is not liable to work loose. The formation of the valve wrist pins with a shoulder 8 and the swaging of the lower core and end of each to 90 force its periphery into contact with the under surface of the material surrounding the eye, insures a rigid permanent connection between the pins and their respective shanks, one which will not work loose during the operation of the valve cover and one 95 which is simple in assembly and may be cheaply manufactured. A valve cover operating arm 11 provided with an aperture 12, having a bushing 13 therein is 100 adapted to receive each pin 9, said arms being pinned on the pins as at 14. The opposite ends of said arms are likewise apertured at 15, and are connected with a crank shaft 16 which shaft when rotated 105 operates the valve seat covers 3 horizontally over their valve seats 2.

I claim:—

A valve seat cover and valve wrist pin assembly for meters comprising a shank 110

cast in said cover and having a portion projecting from one edge of the cover, the projecting portion of said shank provided with an eye extending therethrough, a cylindrical valve wrist pin having a cored end of reduced diameter, the end of reduced diameter affording a shoulder at the base of the wrist pin, said end being received within said eye with the shoulder resting on said

shank surface, said cored end being swaged 10 to cause its periphery to overlie the periphery of the under wall surface of said eye, and seat the shoulder tightly against the upper shank surface.

In testimony whereof I have signed my 15 name to this specification.

GEORGE D. WILSON.
